UNITED STATES PATENT OFFICE.

JACOB A. BAER, OF HONESDALE, PENNSYLVANIA.

AIR VALVE FOR FUEL TANKS.

1,425,358.

Specification of Letters Patent. Patented Aug. 8, 1922.

Application filed May 10, 1920. Serial No. 380,288.

To all whom it may concern:

Be it known that I, JACOB A. BAER, citizen of the United States, residing at Honesdale, in the county of Wayne and State of Pennsylvania, have invented certain new and useful Improvements in Air Valves for Fuel Tanks; and I do hereby declare the following to be a full, clear, and exact description of the invention, such as will enable others skilled in the art to which it appertains to make and use the same.

This invention relates to a valve controlled venting device for containers. It is particularly applicable for use on gasoline tanks for motor vehicles.

The objects of the invention are to provide a valve which under normal conditions of gradual feed of liquid from the container affords free access of air into the tank to equalize pressures as liquid is drawn from the tank; to provide a valve that will permit air to be forced into the tank for raising pressure and retaining the pressure therein above atmospheric, when desired.

In the drawings, wherein similar reference characters designate corresponding parts throughout the several views:

Figure 1 is a perspective of a screw-fitted closure provided with the improved valve;

Figure 2 is a cross section therethrough;

Figure 3 is a plan of the closure cap with valve removed;

Figures 4 and 5 are perspective views of details.

Tanks for containing liquid fuel used in internal combustion engines are provided ordinarily with threaded caps fitted to a filling opening. The filling opening may be internally threaded and the cap externally threaded or the filling orifice may be surrounded by a flange threaded on the outside, and the cap may be provided with a cooperating flange threaded on the inside. My invention is applicable to either of the said types of cap, and in fact, it is not material what the particular form of cap may be. In the drawing the cap illustrated is such as is used on the fuel tank regularly mounted on a Ford car.

The cap 1 shown, is internally threaded, and adapted to be screwed into the sput 2, which is welded or otherwise secured to a tank 3. The cap 1 has, extending transversely, the usual ribs or lugs 4 adapted to be seized by the thumb and fingers, or engaged by a wrench when it is desired to

screw the cap on or off, or to tighten or loosen it.

It is usual to provide a small vent orifice in caps of this sort used in gasoline tanks and the vent orifice is generally located at one side of the centre, in order that air may flow into the tank as the liquid contents thereof are drawn from the tank so that the gasoline or other liquid contents may flow freely under the influence of gravity from the tank to the carburetor or other point of use. In my invention the improved valve and venting device is preferably applied to that part of the cap commonly occupied by the said air venting orifice.

At one side of the center of screw cap 1 is a threaded opening 10^a. Into said threaded opening is screwed a tube 10 having its upper extremity reduced as at 11 and threaded externally, said tube 10 constituting a valve casing and venting nozzle. The casing is bored and counterbored. That portion of the casing or tube below the reduced end has a large counterbore 12 which terminates at its upper end in a valve seat 13, accurately ground to receive a check valve 14, shown of spherical form. From the center of the valve seat 13 a small bore or orifice 13^a extends from the counterbore 12 through the reduced part 11 to the top of the tube 10. Threaded into the lower end of the counterbore in the tube 10 is a plug 16 having a central orifice 17 therethrough, and provided with a notch 18 with which a screw driver may be engaged in order to screw the said plug 16 into the lower end of tube 10. Between the plug 16 and the valve 14 is a coiled spring 19 tending to press the valve 14 against the seat 13 in the tube.

A cap 20, internally threaded, and having extended centrally therefrom a small tube 21 is adapted to be screwed to the top of the tube 10. The small tube 21 is open from end to end and is of a size and length to fit snugly in the orifice 13^a in the reduced portion of the tube 10 and extend down into the larger bore 12 of the said tube 10. The small tube 21, depending from the cap 20, is slotted or kerfed, as at 22, in an axial plane at its lower end and said lower end of the tube 21 is adapted to engage and press the valve 14 away from its seat 13 when the cap 20 is screwed to the top of the tube 10.

Sleeved in a groove around the cap 20 is a split collar 23 adapted to rotate freely with respect to said cap and having a pair of ears 24 connected by a cross pin 24^a which 5 passes through an end link of a chain 25, the other end of which is attached to the tube 10 as at 26. The cap 20 may, therefore, be removed from the tube 10 and remain attached to it by the chain 25 so that 10 it cannot be lost.

In the position shown in Figure 2 the vent is open and gasoline or other liquid flowing from the tank will be replaced by air entering the tank through the tube 21, entering 15 air passing laterally by way of the slits 22 in the lower end of the tube and around the ball valve 14 into the tank by way of orifice 17 in the plug 16. Should it be desired to retain super atmospheric pressure in the 20 tank, the cap 20 should be unscrewed, allowing the valve 14 to be pressed against the seat 13. By the expansive force of the 25 spring 19 supplemented by the outward pressure, if the tank is filled with air, or gases under pressure higher than atmospheric, the valve 14 will remain firmly seated and prevent any outward flow of the air or other gases in the tank through the orifice, thus maintaining any desired pressure 30 necessary to force-feed the liquid contents to the point of use thereof.

When it is desired to increase pressure upon the liquid in the tank in order to feed said liquid contents therefrom, as, for example, when the gasoline is low or the position 35 of the tank is such that gravity is not effective to remove said contents, the cap 20 may be unscrewed and a pump threaded to the reduced end 11 of the tube 10, may 40 be operated to force air past the check valve 14 into the tank. Upon removal of the pump the pressure within the tank will be retained, owing to the seating of the valve 14 under the pressure of the spring 15 and the 45 air or other gas within the tank.

The described structure is very compact. It is adapted to a standard closure cap for gasoline tanks by merely enlarging the usual 50 vent orifice and tapping the tubular valve casing into it. It does not interfere with the adaptability of the standard cap to be screwed on or off or otherwise manipulated, and it adapts the tank to be filled with compressed air, or to be normally vented through 55 one nozzle or casing and one air passage, and to automatically confine the air within the tank under pressure.

What I claim is:

1. The combination of a valve casing having 60 a counterbored passage therethrough, and an exteriorly threaded end, a valve seat at the junction of the bore and counterbore and a check valve in the counterbore adapted to close against said seat, an interiorly 65 threaded cap adapted to fit the exteriorly

threaded end of said casing, said cap having a tube, open from end to end, secured thereto, and adapted to snugly fit the bore or smaller portion of said passage and to press the valve from its seat, said tube having a 70 longitudinal slit in its lower end.

2. The combination in a container having a filling opening, of a threaded closure cap therefor, having a diametrically disposed means whereby it may be rotated, and 75 an orifice at one side thereof, a valve casing fitted to said orifice, a check valve therein adapted to seat under outward pressure, a venting cap adapted to be screwed to the outer end of said casing, said cap having 80 a projecting device arranged to unseat the check valve when said cap is screwed downward on said casing and vent said container or allow the valve to remain seated when said cap is screwed upward thereon. 85

3. The combination in a container having a filling opening, of a closure cap therefor having an orifice therein, a valve casing fitting said orifice, said valve casing having exterior screw threads on its end, a check 90 valve in said casing adapted to seat under outward pressure, a venting cap adapted to be screwed on said threaded end of the valve casing, said venting cap having a means for pressing the valve from its seat to vent the 95 container when the seated cap is screwed down, and to allow the valves to seat when the venting cap is screwed upward, said venting cap having an exterior annular groove, a swiveled ring seated in said 100 groove, and a flexible connection between said ring and said closure cap.

4. The combination of a container having a filling opening, a removable closure for said opening, a venting device on said closure having a venting orifice, a check valve adapted to close the orifice under pressure existing within the container so as to prevent the escape of pressure therefrom when said valve is seated, a spring tending to 110 seat said check valve, and an orificed cap having a stem adapted to unseat the check valve to permit escape of pressure through the orifice in the cap when said cap is closed.

5. The combination of a valve casing having a counterbored passage therethrough, a valve seat at the junction of the bore and counterbore, a ball valve adapted to close against said seat, a coiled compression spring in the counterbore exerting its tension to seat the ball valve, a cap threaded to the outer end of the valve casing, said cap carrying an open ended tube adapted to fit snugly the bore or smaller portion of said passage and to press the ball valve from its 125 seat, said tube having a lateral opening adjacent its lower end to permit venting when the ball valve is depressed.

6. The combination of a container adapted to hold gasoline or the like under pres- 130

sure, said container having a suitable filling orifice to admit liquid and an air inlet and venting device; said air inlet and venting device comprising a valve casing having an orifice therethrough, a valve seat therein, a valve adapted to engage said seat to prevent escape of pressure from the container, a spring for retaining the valve against its seat, and a device adapted to push the valve away from its seat to vent the container at will.

In testimony whereof I affix my signature.

JACOB A BAER.
